UNITED STATES PATENT OFFICE.

VICTOR GAZZOLO, OF STOCKTON, CALIFORNIA.

GREASE-CUP.

1,171,606.

Specification of Letters Patent.

Patented Feb. 15, 1916.

Application filed March 3, 1915. Serial No. 11,720.

To all whom it may concern:

Be it known that I, VICTOR GAZZOLO, a citizen of the United States, residing at Stockton, in the county of San Joaquin, 5 State of California, have invented certain new and useful Improvements in Grease-Cups; and I do declare the following to be a clear, full, and exact description of the same, such as will enable others skilled in 10 the art to which it appertains to make and use the same, reference being had to the accompanying drawings, and to the characters of reference marked thereon, which form a part of this application.

15 This invention relates to improvements in grease cups used on friction bearings of all kinds, the object of the invention being to produce a cup by means of which the grease may be delivered against the bearing in pre- 20 determined amounts and in an automatic manner. This automatic feature is controlled by operation of the machine or machinery of which the lubricated bearing may be a part.

25 A further object of the invention is to produce a structure in combination with that mentioned above, whereby an independent supply of lubricant may be delivered from the cup manually and independent of 30 the automatic feature and without interfering with the structure by which the automatic feature is controlled.

A still further object of the invention is to produce a simple and inexpensive device 35 and yet one which will be exceedingly effective for the purposes for which it is designed.

These objects, I accomplish by means of such structure and relative arrangement of 40 the parts as will fully appear by a perusal of the following specification and claims.

On the drawings, similar characters of reference indicate corresponding parts in the several views.

45 Figure 1 is a side elevation, partly in section, of my improved cup. Fig. 2 is a side elevation of the same taken at right angles to the side shown in Fig. 1 and being partly broken out and in section. Fig. 3 is a top 50 plan view of the cup. Fig. 4 is a sectional view of the upper portion of the cup taken on a line X—X of Fig. 3. Fig. 5 is a top plan view of the ratchet operating wheel of the device showing the mechanism by 55 which the manual delivery of the lubricant

may be had independently of the automatic delivery.

Referring now more particularly to the characters of reference on the drawings, the numeral 1 designates the cup substantially 60 funnel-shaped at its lower end, as at 2, and provided with a central orificed outlet 3.

The numeral 4 designates a removable cap screw mounted into the upper end of the cup 1 and provided with a central orifice 5 65 surrounded at its upper end by a cupped-out recess 6.

The numeral 7 designates a piston movable in the cup 1 and provided with a small hole 8 disposed through which is a small pin 70 9 of lesser diameter than the hole 8, such pin 9 having a flanged head 10 at one end and a small cross pin 11 on the other, whereby it is held in position in said hole 8. The purpose of this hole 8 and pin 9 is to allow 75 of the easy removal of the piston 7 from the cup. When the piston 7 has been pressed down against the grease, the adhesion and suction of the same is such as to make it very hard to remove the piston 7, but by 80 pressing the pin 9 so that the head 10 is pressed away from the hole 8, air may be admitted through said holes to relieve the suction and adhesion between the piston 7 and the grease, whereby such piston 7 may 85 be easily removed from the cup for the purpose of filling the same or for any other desired purposes.

The piston 7 is screw mounted upon a threaded pin 12 depending centrally into 90 the cup 1 and having a square head 13 removably projecting into a shoulder 14 projecting upwardly from a disk 15 disposed in the upper end of the cup and having a projecting annular flange 16 around its 95 outer periphery. The disk 15 and its shoulder 14 are held in position in the cap 4 by means of a nut 17 threaded on the shoulder 14 and normally disposed in the cupped-out recess 6. The shoulder 14 has a square projecting head 18 extending above the nut 17. By applying a wrench to the head 18 and turning the same, this will turn the shoulder 14 and the disk 15 and since the square head 13 projects into the shoulder 14, such head 100 and its pin 12 will be turned. This movement will cause the piston 7 to be advanced on the threaded pin 12 to press the grease out of the cup 1 through the outlet 3 upon the bearing. This is the manually operated 105 110

structure for delivering any quantity of grease at any desired time.

The automatic delivery of the lubricant in predetermined quantities at predetermined times is controlled by means of the following structure, namely: Disposed on the annular flange 16 is a ratchet wheel 19 having a plurality of tapered recesses 20 in its inner periphery. Pins 21 are disposed in these recesses 20 so that when the ratchet wheel 19 is moved in the direction of the arrow shown in Fig. 5, the pins 21 will wedge into the tapering ends of the recesses 20 and thus engage the ratchet wheel 19 in frictional contact with the disk 15 so that with the movement of said ratchet wheel 19, the disk 15, shoulder 14, and pin 13—12 will be turned to advance the piston 7 to force the grease through the outlet 3. The movement of the ratchet wheel 19 is automatically controlled by means of the following structure, namely: Formed on the side of the cup 1 is a barrel 22 having a removable screw cap 23 at its lower end and a removable screw cap 24^a at its upper end and an inwardly projecting guide shoulder 24 intermediate its length. A pin 25 is provided with a roller 26^a at its lower end and projects through the member 23 as a guide and into the barrel 22 and through the guide 24. Such pin 25 is provided with a collar 26 adapted to normally engage the member 23 to fix the predetermined normal position of such pin, which position is maintained by means of a spiral spring 27 disposed around the pin 25 and interposed between the members 23 and 24. The member 23 is held against rotation by means of a locking pin 28. The upper end of the cup 1 is provided with a transverse barrel 29 with a chambered member 30 communicating from the barrel 22 to the barrel 29. The barrel 29 has an opening 31 into the cup 1. Disposed in this barrel 29 is a hollow pin 32 having a pin 33 at one end projecting into the end wall of such barrel 29, the outer end of such pin 32 engaging the end of a removable cap 34 screw mounted in the end of the barrel 29. This cap 34 holds the pin 32 in position and within the hollow pin 32 is a spring 35 which is interposed between the bottom of the pin 32 and the cap 34 to hold such pin 32 in frictional engagement lengthwise so that it will have no tendency to any backward rotary movement when turned in one direction. The upper end of the pin 25 is slotted, as at 36, with a pin 37 projecting across the upper end of the slot. An arm 39 projects into the slot 36 and is provided at its other end with a collar 40 normally surrounding the pin 32. This collar 40 is provided with a plurality of tapered recesses 41 on its inner periphery in which are disposed small pins 42 so that when the collar 40 is moved in the

direction indicated by the arrow in Fig. 1, these pins 42 will wedge between the collar 40 and the pin 32 to cause a frictional engagement between them, whereby, with such movement of the collar 40, the pin 32 will be moved but when the collar 40 moves in the reverse direction, the pins 42 will roll out of the wedged position and allow of a free movement of the collar 40 irrespective of the pin 32. Any tendency of the pin 32 to follow this return movement is overcome by the friction spring 35, as set forth above. The pin 32, adjacent the opening 31, is provided with a small worm gear 43 engaging with the ratchet wheel 19 so that movement of the pin 32 is imparted to such ratchet wheel 19 to move it in the direction of the arrow shown in Fig. 5. Hence, with the movement of the said pin 32, the piston 7 will be moved in the manner heretofore described. Movement is imparted to the pin 32 by means of the vertical movement of the pin 25 imparted through the arm 39 and collar 40, as described. This pin 25 is automatically moved by means of a cam 44 mounted on a shaft 45 driven in any suitable manner by the machine or machinery to which the bearing to be lubricated may be attached. This cam 44 engages the roller 26^a, so that with each revolution of the shaft 45, the pin 25 will be lifted to operate the piston 7 through the medium of the structure detailed above. After each lift, the spring 27 will return it to its lower position again.

From the foregoing description it will be seen that there is an automatic delivery of a predetermined quantity of grease through the outlet 3 through each lift of the pin 25 and a manual delivery of the lubricant will be had in any quantity by turning the head 18 which will, by reason of the release of the wedge pins 21, allow the piston 7 to be advanced without disturbing the automatic structure.

From the foregoing description it will readily be seen that I have produced such a device as substantially fulfills the objects of the invention as set forth herein.

While this specification sets forth in detail the present and preferred construction of the device, still in practice, such deviations from such detail may be resorted to as do not form a departure from the spirit of the invention, as defined by the appended claims.

Having thus described my invention what I claim as new and useful and desire to secure by Letters Patent, is:

1. A device of the character described comprising a grease cup having an outlet, a piston movable in said cup, a pin movable vertically adjacent said cup, an arm engageable by said pin, a worm gear mounted adjacent said cup, said arm being adapted to

engage said worm gear to impart rotary motion to the latter, a ratchet wheel disposed within said cup and engageable by said worm gear, and means interposed between 5 said ratchet wheel and said piston whereby with the movement of said ratchet wheel said piston will be moved, as described.

2. A device of the character described comprising a grease cup having an outlet, a piston 10 movable in said cup, a turnable pin adapted to operate said piston, and means for turning said pin, such means comprising a turnable disk in the upper end of said cup engaging said pin, means for manually turning said 15 disk, a ratchet wheel disposed around said disk and provided with a plurality of tapered recesses in its inner periphery, pins disposed in said recesses and adapted to be brought into frictional engagement between said 20 ratchet wheel and said disk when said ratchet wheel is turned in one direction, and means for moving said ratchet wheel a predetermined distance at predetermined times, as described.

25 3. A device of the character described comprising a grease cup having an outlet, a piston movable in said cup, a pin movable adjacent said cup, a pin disposed transversely with respect to said first-named pin, an arm 30 engageable with said first named pin and provided with a collar surrounding said transverse pin, said collar being provided with a plurality of tapered recesses, pins in said recesses adapted to wedge between said collar 35 and said transverse pin when the collar moves in one direction, a worm gear on said transverse pin, a ratchet wheel within said cup engageable by said worm gear, and means interposed between said ratchet wheel 40 and said piston whereby with the movement

of said ratchet wheel said piston will be moved, as described.

4. A device of the character described comprising a grease cup having an outlet, a piston movable in said cup, a ratchet wheel disposed within said cup, means interposed between said ratchet wheel and said piston whereby with the movement of said ratchet wheel said piston will be moved, a hollow pin 45 disposed transversely adjacent said cup and provided with a worm gear engaging said ratchet wheel, a tension member disposed within said hollow pin to hold said pin against undesired rotary movement, a collar disposed around said rotary pin and 50 adapted to be frictionally engaged therewith when moved in one direction, and means for intermittently rotating said collar, as described.

5. A device of the character described comprising a grease cup having an outlet, a piston movable in said cup, a ratchet wheel disposed within said cup, means interposed between said ratchet wheel and said piston whereby with the movement of said ratchet 60 wheel said piston will be moved, a pin disposed transversely adjacent said cup and provided with a worm gear engaging said ratchet wheel, a collar disposed around said rotary pin and adapted to be frictionally engaged therewith when moved in one direction, and means for intermittently rotating 65 said collar, as described.

In testimony whereof I affix my signature in presence of two witnesses.

VICTOR GAZZOLO.
